FURNACE SUPPORT

Frank Schneider and Michael Schneider,
Cleveland, Ohio

Application November 1, 1939, Serial No. 302,405

3 Claims. (Cl. 126—99)

This invention relates to furnace supports and has for an object to provide posts adapted to extend from the radiator of a hot air furnace to the floor and having brackets bolted to the upper section of the fire pot, the posts bearing the weight of the upper section of the furnace, which ordinarily rests upon the fire pot and when the fire pot is intensely hot the weight of the upper part of the furnace often causes the fire pot to crumple or break.

A further object of the invention is to provide a device of this character which may be applied to old as well as new furnaces, which will be formed of a few strong simple and durable parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawing forming a part of this specification:

Figure 1 is a top plan view of a hot air furnace equipped with supports for the upper portion of the furnace constructed in accordance with the invention.

Figure 2 is a side elevation of the furnace and supports shown in Figure 1 with portions broken away.

Referring now to the drawing in which like characters of reference designate similar parts in the various views, 10 designates the ash pit and base of a furnace, 11, 12 and 13 designate superposed fire pot sections, and 14 designates the radiator of a hot air furnace. In carrying out the invention preferably three posts 15 are mounted underneath the radiator to extend from the radiator to the floor 16 and support the weight of the radiator and upper section 13 of the fire pot, thus relieving the lower sections of 11 and 12 of the weight of these parts and accordingly preventing crushing of the lower sections 11 and 12 of the fire pot when these sections become exceedingly hot.

Each post comprises an upper section 17, and a lower section 18, both sections being provided with threaded bores at their confronting ends, which ends are spaced apart to receive a threaded adjusting pin 19.

Lock nuts 20 are disposed on the pin and bear against confronting ends of the upper and lower

sections 17 and 18 to properly adjust these sections vertically to support the weight of the radiator and upper fire pot section 13.

The posts are connected to the upper fire pot section 13 by respective angular brackets 21 each having a leg 22 disposed horizontally and receiving the adjusting pin 19. Lock nuts 23 secure the bracket arm to the pin. The leg 22 is provided with apertured lugs 24, best shown in Figure 1, through which bolts 25 are engaged and threaded into the upper section 13 of the fire pot. Each bracket is provided with a vertically disposed leg 26 which carries a set screw 27 that bears against a pillow washer 28 disposed on the upper section 13 of the fire pot. The set screw is adjusted to level the horizontal leg 24.

In operation the weight of the radiator 14 and the weight of the upper section 13 of the fire box is borne by the posts 15 so that the lower sections 11 and 12 of the fire pot are relieved of this weight and may become intensely hot without being crushed.

From the above description it is thought that the construction and operation of the invention will be fully understood without further explanation.

What is claimed is:

1. The combination with a hot air furnace having a radiator and having superposed fire pot sections, of a plurality of posts extending from the radiator to the floor, and brackets connecting the posts with the uppermost fire pot section, said posts supporting the weight of the radiator and upper fire pot section.

2. The combination with a furnace having a radiator and a plurality of superposed fire pot sections, of a plurality of posts extending from the radiator to the floor, each post comprising an upper section and a lower section, both sections being provided with threaded bores at their spaced confronting ends, a threaded adjusting pin secured in said bores, lock nuts on the pin bearing against said ends, brackets each having a horizontally disposed leg engaging said pins, lock nuts on the pins engaging said leg, and means securing said leg to the uppermost fire pot section, said posts supporting the weight of the radiator and the uppermost fire box sections.

3. The combination with a furnace having a radiator and a plurality of superposed fire pot sections, of a plurality of posts extending from the radiator to the floor, each post comprising an upper section and a lower section, both sections being provided with threaded bores at their spaced confronting ends, a threaded adjusting

pin secured in said bores, lock nuts on the pin bearing against said ends, brackets each having a horizontally disposed leg engaging said pins, lock nuts on the pins engaging said leg, means securing said leg to the uppermost fire pot section, said bracket each having an upstanding leg, and a set screw carried by the upstanding

leg bearing against the uppermost fire pot section for leveling the horizontal leg of the bracket, said posts supporting the weight of the radiator and the uppermost fire pot section.
